SHEARS

John Herman Medlen, Red Cloud, Nebr.

Application January 27, 1941, Serial No. 376,199.

4 Claims. (Cl. 30—228)

The present invention relates to improvements in shears and more particularly to the type used for clipping or shearing sheep.

An important object of the invention resides in the provision of shears including a novel type of compressed air means for operating the shearing or clipping knife.

Another object of the invention is to provide an improved shears comprising a stationary and a reciprocating knife, the reciprocating knife being driven by a compressor which is encased in the handle of the shears and under constant control of the operator.

A further object of the invention is to provide shears of the above character, the construction of which permits the shearing of sheep in a rapid and efficient manner while reducing to a minimum the possibility of cutting or otherwise injuring the bodies of the sheep.

A still further object of the invention resides in the provision of shears, the cutting blade of which is adapted to be operated by compressed air which is admitted to the shears by a flexible tubing, the construction of which gives the operator more freedom of movement in shearing around the legs, neck, etc., of the sheep materially facilitating the sheep shearing operation.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a side elevational view partly in vertical section taken on line 1—1 of Figure 2.

Figure 2 is a longitudinal sectional view taken substantially on line 2—2 of Figure 1.

Figure 3 is a vertical sectional view taken substantially on line 3—3 of Figure 1.

Figure 4 is a side elevational view of the rear face of the shears.

Figure 5 is an enlarged detail elevational view illustrating the manner of associating the reciprocating cutting blade with the air compressor.

Figure 6 is a detail sectional view taken substantially on line 6—6 of Figure 1.

Figure 7 is a detail top plan view of one section of the shears.

Referring to the drawing for a more detailed description thereof, the improved shears are generally designated by the reference numeral 8 and

include a casing 9 provided at its lower edge with teeth 10. The casing 9 is substantially rectangular-shaped and extending rearwardly therefrom is a hollow elongated handle 11 adapted to be engaged when operating the shears. As best shown in Figures 1 and 2 of the drawing, the handle 11 is of hollow formation, access thereto being obtained through the plate 12 removably held by means of the fastener 13.

A blade 14 having teeth 15 formed on its bottom edge is mounted within the casing for reciprocating movement with relation thereto, said blade having its upper edge 16 reduced in thickness for engagement in back of a lip 17 formed on the upper edge of the casing 9. As is to be readily understood, the blade 14 reciprocates freely when driven by a compressor to be herein-after described with the reduced edge 16 and lip 17 serving to retain the blade in contactual relation with the casing. The blade 14 is held under tension by means of an elongated spring 18, the ends of which engage studs 19 carried by the casing 9 and which are held thereon by means of thumb nuts or the like 20. Tension of the blade can be increased or decreased by tightening or releasing the thumb nuts 20.

The portion of the casing 9 adjacent the handle 11 near the upper end thereof is extended as indicated at 21 to form a cylindrical motor chamber 22. A rotor 23 is mounted on its shaft 24 within a bearing 25 positioned in the chamber 22, the periphery of said rotor being formed with a multiplicity of pockets 26 which receive a charge of compressed air for driving the rotor. A circular groove 27 is formed in one face of the rotor and eccentrically thereof in which is disposed a pin 28 projecting from the blade 14. The pin 28 travels in the groove 27 as motion is imparted to the rotor 23 for driving the blade 14 in a reciprocatory manner.

The rotor 23 is completely enclosed so that the compressed air will effectively drive the same, the blade 14 forming the front wall of the enclosure. As shown in Figure 2, a boss 29 extends from the casing 9 and cooperates to form one wall of the motor chamber and the blade 14 is offset laterally as indicated at 30 overlapping the boss 29 and cooperating with the casing 9 to form a closed chamber for the rotor. The offset portion 30 is of such a size that as the blade 14 is reciprocated and reaches its outward limit, it will still encase the rotor.

Air under pressure for driving the rotor 27 is delivered thereto through the nozzle 31 coupled as indicated at 32 with a tube 33, said tube ex-

tending longitudinally of the handle and adapted to have its rear end 34 connected by a hose to a source of supply. A valve, of conventional construction, is disposed in the connection 32 being under the control of a button 35 projecting upwardly from the handle 11. The button 35 is formed with a stem 36 having connection with a lever 37 attached to the valve and upon depressing the button against tension of the spring 38, the valve is opened to admit air to the rotor and upon the release of pressure on the button the spring 38 returns the same to normal position closing the valve through the lever 37. The air is exhausted from the rotor through the outlet 39 formed in the casing 9.

The casing 9 is provided at its front end with a shock absorber consisting of a spring 4 disposed on a stem 41. The end of the blade 14 is bent at right angles as indicated at 42 and is normally in contact with the spring 40 so that movement of the blade towards the handle compresses the spring to prevent undue shock to the blade.

An elongated roller 43 is attached to the rear side of the casing 9, said roller being journaled in brackets 44 and as more particularly shown in Figure 3 of the drawing the roller 43 is partially embedded in the rear wall of the casing. The roller functions when the shears are in cutting position and aids in maintaining them at the correct angle for properly shearing the sheep.

It is thought that the operation of the shears is readily apparent from the above description when taken in connection with the accompanying drawing. The rotor 23 is under the constant attention of the operator of the shears and the amount of air is controlled by operation of the button 35 for increasing or decreasing the speed of the rotor and likewise the reciprocatory motion of the cutting blade 14. The operator grasps the handle 11 and places the shears with the roller 43 against the body of the sheep and the rotor 23 is started by depressing the button 35 to open the valve in the nozzle 31. Rotation of the rotor drives the blade 14 through its pin connection 28 in engagement with the eccentric groove 27. The handle 11 is arranged relative to the casing 9 so as to give the operator complete vision of his work at all times with the resultant less danger of injury to the body of the sheep. The roller 43 in addition to maintaining the shears at a proper angle serves to roll out the wrinkles of the body of the sheep to minimize the possibility of cutting the skin. The air outlet 31 will discharge the cut wool away from the sheep and at the same time aid in removing dirt, dust and the like from the sheared wool.

Also it will be understood, of course, by those skilled in the art that variations in the hereinabove described device involving the substitution of substantial equivalents for the devices described are intended to be comprehended within the spirit of the present invention and that the

invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In a shearing implement, a body having cutting teeth formed at one edge thereof, a reciprocatory blade mounted on the body having cutting teeth in cooperative relation with the teeth of the body, means mounted on the body and connected with the blade for reciprocating the latter, and a roller rotatably mounted on the body on the side opposite the blade for guiding the movement of the cutting teeth.
- 10 2. In a shearing implement, an elongated body having cutting teeth formed along a longitudinal side edge thereof, a blade slidably mounted on the body having cutting teeth in co-acting relation with the teeth on the body, a rotor journaled on the body, a nozzle disposed to direct fluid under pressure against the rotor for rotating the same, a spring pressed valve operable to control the passage of fluid through the nozzle, and means connecting the blade with the rotor for reciprocating the blade during rotary operation of the said rotor.
- 15 3. In a shearing implement, an elongated body having cutting teeth formed along a longitudinal side edge thereof, a blade slidably mounted on the body having cutting teeth in co-acting relation with the teeth on the body, a rotor journaled on the body, a nozzle disposed to direct fluid under pressure against the rotor for rotating the same, a spring pressed valve operable to control the passage of fluid through the nozzle, the said rotor having an annular groove formed eccentrically in one side thereof, and a pin attached to the blade and engaging the said annular groove whereby rotation of the rotor will impart reciprocatory movement to the blade.
- 20 4. In a shearing implement, an elongated body having cutting teeth formed along one longitudinal edge thereof, a blade slidably connected with the body having cutting teeth in co-acting relation with the cutting teeth of the body, a rotor journaled on the body, means connecting the rotor with the blade for reciprocating the latter upon rotation of the rotor, a nozzle mounted on the body and positioned to direct air under pressure against the rotor to rotatably drive the same, a valve mounted to control the passage of compressed air through the nozzle, a member slidably mounted on the body and connected with the valve for operating the same, and a spring pressed element attached to the said valve actuating member operative to yieldingly close the valve and manually compressible to open the valve to effect operation of the rotor and blade.
- 25 5. JOHN HERMAN MEDLEN.
